ABSTRACT

Wood chipper has rotating chipper disc and fan wheel spaced from disc against which fan wheel chips impinge. Fan wheel provided with impact plates in area of impact of chips to provide low angle of impact to impinging chips to minimize chip damage.

PULPWOOD CHIPPER

BACKGROUND OF THE INVENTION

In the making of paper pulp from wood and particularly in utilizing a chemical pulping process it is desirable that the wood chips be uniform in size both in width and length as well as in thickness, and that the chips have a minimum content of small slivers or pins and sawdust-like particles.

Wood chips are conventionally obtained by passing logs or wood scraps through a chipper which comprises a massive rotating disc having radially extending knives arranged to cut off the ends of the wood or logs fed into the chipper. The disc is provided with passageways adjacent the knives so that the severed chips may pass to the rear of the disc. In one type of chipper a fan wheel is mounted behind the disc and is provided with blades which are adapted to engage and propel the chips and also the surrounding air so as to blow the chips out of the chipper and for a substantial distance therefrom. The geometry of prior chippers has been such that the blades have engaged the chips with a relatively high differential velocity with substantial damage to the chips and production of large amounts of undesirable slivers, pins and sawdust-like particles. In addition, in prior chippers the chips have impacted against the side surface of the fan wheel at a relatively high velocity and a high incidence angle causing further breakage of the chips.

BRIEF DESCRIPTION OF THE INVENTION

It is an object of the present invention to provide a configuration for a blowing discharge chipper which will minimize damage to chips.

The chipper of the invention comprises a rotary cutter disc with the usual substantially radial knives for cutting chips from a log or wood piece fed to the disc. Mounted rearwardly of the cutter disc is a fan wheel having impeller blades on the periphery for engaging and propelling chips and air. It will be appreciated that chips will be severed from logs or wood pieces and will travel towards the fan wheel in short bursts along the same path and will strike the fan wheel adjacent its periphery in areas spaced around the wheel as such areas rotate into the path of the chips. In accordance with the present invention, the fan wheel is provided with impact means on the surface thereof defining a low angle of impact to the chips at such impact areas so as to minimize breakage of the chips.

For a more detailed description of the invention reference is made to the accompanying drawings.

DRAWINGS

FIG. 1 is a perspective, semi-schematic view of a chipper constructed in accordance with the invention with certain parts indicated in phantom and others broken away to illustrate certain details;

FIG. 2 is a horizontal section on a reduced scale of a chipper constructed in accordance with the invention;

FIG. 3 is an enlarged fragmentary perspective view of the fan wheel; and,

FIG. 4 is an enlarged fragmentary view of the chipper disc and fan wheel illustrating the chip path.

DETAILED DESCRIPTION OF THE INVENTION

The illustrated chipper comprises a chipper disc 10 mounted on a horizontal shaft 12 which may be driven by any suitable drive means (not shown). The shaft 12 is suitably supported as by trunnions 14 which in turn are suitably supported on a rigid base (not shown). The illustrated chipper is of the horizontal infeed type having an infeed spout 20 through which logs or wood pieces may be fed to the chipper disc 10. As will be apparent, the invention is equally applicable to chippers having a vertically inclined feed spout.

The chipper disc 10 is enclosed within a protective coaxial housing 22 the front wall 24 of which is provided with an opening communicating with the spout 20.

The chipper disc 10 may be of any conventional construction and is provided with a plurality of removably mounted knives 28 which project from the front face thereof, the disc having openings or slots 29 (FIG. 4) adjacent to each of the knives through which the severed chips may pass from the front to the back of the disc 10 as they are severed from logs fed through the infeed spout 20.

Mounted on the shaft 12 rearwardly of the disc 10 with respect to the spout 20 is a wheel 30 which may be, for example, a flywheel or fan wheel. The fan wheel 30 is enclosed within a housing 32 provided with a tangential outlet 34 at the top thereof. The fan wheel 30 is provided with a plurality of impeller or fan blades 36 having a portion extending outwardly from the periphery of the wheel but also having a portion which extends outwardly from the side face 38 of the wheel 30 adjacent the chipper disc 10. The peripheral portion at least of the face 38 is planar and perpendicular to the axis of rotation of the wheel 30. The housing 32 is coaxial with the fan wheel 30 and the blades 36 are sized so as to provide relatively close clearance between the housing and the edges of the blades to prevent accumulation of chips between them. Extending between and communicating with the disc housing 22 and the fan wheel housing 32 is a tunnel 40 through which chips may pass as they are severed by the cutter disc 10.

In a chipper of the type illustrated, the cutter disc 10 is rotated at a relatively high velocity, for example, at a speed of from 200 to 720 revolutions per minute and the disc may have a diameter up to 3,000 centimeters. A chip which is severed from a log or other piece of wood has a velocity imparted to it which is roughly 20 percent greater than the tangential velocity of the knife 28 at the point of impact. Thus, in a chipper rotating at 300 rpm and having a cutter disc diameter of 3,000 centimeters, a chip cut from a piece of wood contacted by a knife at a point near the periphery of the cutter disc can have a velocity in the order of about 156 feet per second, or about 4,900 centimeters per second. Chips cut in positions closer to center of the disc 10 will have a lesser velocity. Chips of the higher velocities which are severed with a chipper such as illustrated will suffer substantial damage when they impact upon a surface at a large angle, that is, an angle greater than about 45°. By damage is meant fracture and rupture of the chips so as to form small fines and particles which are unsuitable in the making of pulp and interfere with the pulp making process.

Chips severed from the raw material pass through the slots 29 in the disc adjacent each of the knives in a substantially uniform path. In the chipper of the invention the disc 30 is positioned so that the path of the chips will be intercepted by the disc adjacent the periphery thereof. As will be apparent, the chips will travel in bunches, that is, each knife will cut off a group of chips which will pass through the opening adjacent the knife. There will be a short interval of time between each group of chips as one knife leaves the cutting position and the next knife on the disc reaches the cutting position.

Accordingly, the chips will impact upon the disc 30 at circumferentially spaced areas adjacent its periphery there being an impact area for each of the knives. Such impact areas are quickly discernible when a cutter is put into operation by the evidence of wear or removal of paint upon the surface of the wheel 30 at the areas of impact.

With most chips severed in a chipper of the type described and particularly with the chips to which higher velocities are imparted, the angle of impact on the surface 38 of the disc 30 is so great as to cause damage. This angle may be of the order of 60°. Furthermore, while the chips have a tangential component of motion in the direction of rotation of the fan wheel 30, this velocity component is substantially less than the velocity of the fan wheel 30 as a consequence of which radial blades striking such chips may have a substantially high relative velocity and cause damage to such chips.

Accordingly, in accordance with the present invention such chip damage is minimized by providing impact means on the surface of the fan wheel 30 facing the cutter disc 10 which define impact surfaces for the chips having an included angle with respect to the path of travel of the chips less than about 40° whereby the chips suffer minimum damage upon impact. Referring to FIGS. 3 and 4, in accordance with the invention, the fan blades 36 are positioned around the periphery of the wheel 30 so that there is one fan blade 36 adjacent to but rearwardly of each impact area on the peripheral portion 38. The blades 36 each comprise an L-shaped plate 44 including a fan portion 46 which extends radially upwardly from the periphery of the wheel 30 and also extends beyond the face 38 of the wheel 30 toward the cutter disc 10. The plate 44 also includes a leg 47 which extends radially inwardly along the wheel face 38. The plate 44 is secured to the flywheel 30 by a flange 48 extending from the leg 47 along the face 38 and bolts 50 extending through the flange 48 and wheel 30. The plate 46 is braced by gussets 52 and a backup plate 54 extending across the periphery of the wheel 30. Extending angularly inwardly from the top edge of the leg 47 of each of the plates 36 toward the side surface of the wheel 30 is a plate 60. The plate 60 is angled such that its angle of impact with a chip having a path shown in dotted line 62 (FIG. 4) coming from a knife 28 will be less than 40° and preferably at an angle less than about 35°. The plate 60 is planar in its upper portion and has a flat toe 64 extending along the surface 38 of the wheel 30. The toe 64 is secured by bolts to the wheel 30 the head portion of which bolts is preferably recessed in the surface of the plate so as to provide no projecting impacting surface. The forward edge of the

flat toe 64 is tapered as indicated at 68 for the same reason and preferably a curved transition section 66 is provided between the toe 64 and the main portion of the plate 60. Chips striking the plate 60 along the trajectory 62 will rebound at an angle approximately half of the impact angle and thus will be projected forwardly in a direction substantially parallel to the side surface 38 of the wheel 30 and in its direction of rotation. Some will tend to slide along the plate and the transition 66 is provided to assist in the smooth transfer of the chips to the surface 38. The direction of impact will also be towards the periphery of the wheel so that the chips will eventually be engaged by the fan portion 46 of the wheel and be blown out of the top exit 34.

Provision of low impact surfaces as defined by the plate 60 will result in substantial reduction in the percentage of fines which are produced in the chipping operation.

Having illustrated and described a certain preferred embodiment of the invention, it should be apparent that the invention permits of modification in arrangement and detail.

I claim:

1. Apparatus for producing wood chips comprising: a rotary cutter disc having a plurality of substantially radial knives along one face of said disc for cutting chips from lengths of wood fed toward said face, and passageways through said disc for permitting the severed chips to pass through said disc,

a wheel mounted on the side of said disc opposite said one face in spaced relation to and coaxially with said cutter disc, and adapted to be driven in the same direction of rotation as said disc, said wheel being mounted so as to intercept the path of travel of chips cut by said cutter disc knives, and impact means on the surface of said wheel facing said disc defining impact surfaces for said chips having an included angle with respect to said path of travel of less than 40°.

2. An apparatus claimed in claim 1 wherein said impact means comprises plates mounted on said wheel adjacent the periphery thereof and extending at an acute angle from said wheel surface.

3. An apparatus as claimed in claim 2 wherein said plates each comprises a curved portion and a flat portion extending at an acute angle from said wheel surface, said curved portion providing a transition between said wheel surface and said flat portion.

4. An apparatus as claimed in claim 1 wherein said wheel has a plurality of fan blades extending therefrom for accelerating chips and air so as to convey the chips a substantial distance from the apparatus.

5. An apparatus as claimed in claim 3 wherein said flat portion extends at an angle of about 30° with respect to a plane normal to the axis of rotation of said wheel.

6. Apparatus for producing wood chips comprising: a rotary cutter disc having a plurality of substantially radial knives along one face of said disc for cutting chips from lengths of wood fed toward said face, and passageways through said disc for permitting the severed chips to pass through said disc, a wheel mounted on the side of said disc opposite said one face in spaced relation to and coaxially with said cutter disc, and adapted to be driven in the same direction of rotation as said disc,

said wheel being mounted so as to intercept the path of travel of chips cut by said cutter disc knives, the peripheral portion of the surface of said wheel facing said disc being substantially planar and perpendicular to the axis of rotation, a plurality of fan blades mounted on said wheel and projecting from said peripheral surface portion of said wheel toward said disc,

an impact surface defining plate sloping from the outer edge of each of said fan blades to said peripheral surface portion in the direction of rotation of said wheel whereby chips severed at said disc will impact on said plate and be accelerated thereby in the direction of rotation of said wheel.
